UNITED STATES PATENT OFFICE.

JAMES H. KLIPSTEIN, OF MARSHALL, VIRGINIA.

STOVE.

SPECIFICATION forming part of Letters Patent No. 643,382, dated February 13, 1900.

Application filed December 31, 1898. Serial No. 700,792. (No model.)

To all whom it may concern:

Be it known that I, JAMES H. KLIPSTEIN, a citizen of the United States, residing at Marshall, in the county of Fauquier and State of Virginia, have invented a new and useful Stove, of which the following is a specification.

The purpose of the present invention is to secure economy in the consumption of fuel and make available a maximum amount of the heat, which is generally lost by the same passing off with the products of combustion through the smoke-pipe.

The subject-matter of the invention is a stove of the wood-burning variety and constructed chiefly of sheet metal, and in its organization the stove comprises a hot-air drum or space between the fire-box or combustion-chamber and the outer shell or body of the stove, said drum or hot-air space being surrounded by a space through which the smoke and products of combustion pass on their way to the smoke-pipe, thereby separating the greater part of the heat from the gases by radiation and convection prior to the escape of said gases into the atmosphere by way of the smoke-pipe.

For a full understanding of the merits and advantages of the invention reference is to be had to the accompanying drawings and the following description.

The improvement is susceptible of various changes in the form, proportion, and the minor details of construction without departing from the principle or sacrificing any of the advantages thereof, and to a full disclosure of the invention an adaptation thereof is shown in the accompanying drawings, in which—

Figure 1 is a perspective view of a stove for attaining the objects of this invention. Fig. 2 is a vertical central longitudinal section thereof. Fig. 3 is a plan section of the complete stove about on the line X X of Fig. 2. Fig. 4 is a perspective view having the outer shell and the top removed. Fig. 5 is a side elevation of a modification, parts being broken away. Fig. 6 is a transverse section of the construction shown in Fig. 5. Fig. 7 is a detail view of the lower end of the vent-pipe, the full lines showing the parallel slits and the dotted lines showing the portions sepa-

rated by the slits bent upwardly, forming the guards. Figs. 8, 9, and 10 show different arrangements of the flanges for securing a circulation of the products of combustion. Fig. 11 is a detail view showing an air-tube extending across the smoke-space for supplying air to the air-space.

Corresponding and like parts are referred to in the following description and indicated in the drawings by the same reference characters.

The stove in its general appearance may have any desired outline, and, as shown, is of oblong form, being oval or elliptical in plan view, which is the shape found most desirable in heaters of this type.

The stove is mounted upon legs 1 in order to support it a distance from the floor or other surface, so that air may circulate beneath the bottom and pass upwardly through openings in said bottom into and through the air space or drum. The body or outer shell 2 is mounted upon the bottom 3 and is secured thereto in any of the usual ways and is closed at its upper end by a top 4, which is supplied at one end with a collar 5, to which is fitted a smoke-pipe (not shown) in the ordinary way. An opening is had in the top 4 and is closed by a cover 6, and admits of fuel being placed into the fire-box or combustion-chamber 7.

The hot-air space or drum is formed by inner and outer shells 8 and 9, disposed so as to inclose a space between them, said drum being of a shape corresponding to the outline of the stove and having the shells joined at their ends and separated, as shown at 10. The shells 8 and 9 are concentric and the space formed between them is of uniform width throughout its length. A plate 11 extends across the space 10 and is joined to the end portions of the outer shell 9 and is provided at its lower end with an opening 12 and at its upper end with a corresponding opening controlled by means of a damper 13. The damper 13 is vertically disposed, and its stem 14 passes through an opening in the top 4, thereby admitting of the damper being operated from a point without the stove. The space inclosed by the hot-air drum or by the inner shell 8 thereof constitutes the fire-box or combustion-chamber 7, and air is supplied to the lower end of this space by means of a

vent-pipe 15, the latter being located at the end of the fire-box directly opposite the space 10 formed between the terminal portions of the hot-air drum.

5 The vent-pipe 15 has its upper end passing through an opening in the top 4 and cut away at one side. A cap 16 is fitted upon the projecting end portion of the vent-pipe 15 and has formed in one side an opening 17, which 10 is adapted to be brought in register with the cut-away side of the vent-pipe, so as to admit air into the fire-box for supporting combustion. The cap 16 is provided with a handle and is rotatably mounted upon the upper end 15 of the vent-pipe and can be turned so as to close the vent-pipe or regulate the draft to the fire. The lower end of the vent-pipe is formed at one side with a series of slits, and the portions formed between the slits are bent 20 about at right angles to the length of the pipe and project into the fire-box, forming a series of guards 18, which prevent the fuel from crowding into the opening and shutting off the draft. These guards 18 are radially dis- 25 posed and are spaced apart at their outer ends and insure the air being properly admitted into the fire. These guards 18 may of course be made of cast-iron.

A space 19 is formed between the hot-air 30 drum and the body or outer shell 2 and is in communication with the smoke-pipe (not shown) by means of the collar 5 and with the fire-box through the opening 12 and the opening controlled by the damper 13. By having 35 the smoke-pipe located at the end remote from the opening 12 the heat and products of combustion are compelled to pass through the smoke-space 19 before they can escape, and the smoke and gases in their travel through 40 this space heat the body 2 and the outer wall or shell 9 of the hot-air drum, whereby the air in contact with said shells is heated by radiation and convection. In order to retard 45 the passage of the hot air and gases through the space 19, plates, flanges, or strips 20 are provided and extend across the space 19 formed between the shells 2 and 9. The lower plate or flange is interrupted at the rear end of the stove, as indicated at 21, and the upper plate 50 or flange is interrupted at the front end of the stove and at a point diametrically opposite the space 21 formed between the intercepted ends of the lower flange. When the fire is 55 burning briskly or is well started and it is required to utilize the heat to the best possible advantage, the damper 13 is closed, thereby compelling the hot air and products of combustion to pass from the fire-box out through the opening 12 and into the space below the 60 lower flange or plate 20 to the rear of the stove, and thence into the space formed between the two flanges or plates toward the front of the stove and into the space formed above the upper flange or plate and again rearward and 65 out through the collar 5 and the smoke-pipe fitted thereto. The products of combustion and hot air in making this tortuous path have

the greater part of the heat eliminated therefrom by radiation, so that but very little heat is lost, the greater part being made available 70 for heating purposes.

The cold air enters the lower end of the space formed between the shells comprising the hot-air drum through openings 22 formed in the bottom 3 and, passing through said space, is 75 heated and escapes through corresponding openings 23 in the top 4, opposite and in register with the hot-air space. In some forms of the invention cold air will be supplied to the hot-air drum through lateral openings or 80 passages 24 extending through the shells 2 and 9. In this construction the plates, flanges, or parts 20 will be duplicated and the companion strips or plates arranged in close relation, so as to form between them the pas- 85 sages 24, which open into the air-space of the drum and out through the body or shell 2. The flanges, plates, or strips 20 may be horizontal or slightly inclined, as desired, and their number may be varied according to the 90 size and arrangement of the stove.

Fig. 10 shows the flanges running spirally around the drum. The smoke-pipe may communicate with the top, front, or back of the stove-body, according to the style of the stove. 95 Air may be supplied to the air-space 22 by lateral tubes 22^a, as indicated in Fig. 11. A partition 25 subdivides the air-space 22 and is formed of iron and acts to absorb heat and to give it out gradually, and thus maintain a 100 more or less constant temperature under fluctuations in temperature of the stove proper.

Having thus described the invention, what is claimed as new, and desired to be secured by Letters Patent, is—

1. In a stove, the combination with a body, of a hot-air drum located within said body and consisting of inner and outer walls joined at their ends and spaced apart, a plate extending across the space between said closed 110 ends, an outlet-opening at the base of said plate, a second outlet-opening at the top of the plate and having a damper, a smoke-pipe communicating with the space formed by the inner wall of the drum and by the plate, and means for admitting air into said space, substantially as described.

2. In a stove, the combination with the fire-box, of a vent-pipe passing into the fire-box and having its lower end formed with a series of slits and having the parts between the slits bent outwardly forming guards, substantially as and for the purpose set forth.

3. In a stove, the combination with a fire-box, of a vent-pipe passing into the fire-box 125 and having its upper or outer end portion projecting beyond the stove and having a side portion cut away and having its lower ends formed with a series of spaced projections constituting guards, and a cap rotatably 130 fitted upon the upper projecting end of the vent-pipe and having an opening in its side, substantially as described.

4. In a stove, the combination with a body,

of a hot-air drum consisting of inner and outer spaced walls or shelves joined at their ends, said ends being spaced apart, a plate extending across the space between the separated 5 ends of the drum and provided with openings in its upper and lower portions, and a damper controlling the upper opening, the said drum and plate being located wholly within and separated from the outer wall or 10 body of the stove and entirely inclosing the fire-pot, substantially as described.

5. In a stove, the combination with a body having openings in its top and bottom, of a hot-air drum entirely inclosed within and 15 separated from the body and consisting of inner and outer shells joined at their ends and having said ends spaced apart, the hot-air space between said shells communicating with the openings in the top and bottom of the 20 body, a plate closing the open end of the drum and provided with a damper, and means for admitting air to the combustion-chamber independently of said damper, the drum and plate being located wholly within and separated from the body of the stove and 25 completely surrounding and inclosing the fire-pot, substantially as described.

6. In a stove, the combination of a hot-air drum located within the body and forming a 30 fire-box and a smoke-space and having upper

and lower openings, a damper for controlling the upper opening, a series of flanges strips or plates subdividing the smoke-space and intercepted at opposite ends of the stove forming escape-openings, and lateral passages extending across the smoke-space for admitting cold air into the hot-air drum at points between its upper and lower ends, substantially as described. 35

7. In a stove, the combination with a body, 40 of a hot-air drum located within said body and consisting of inner and outer walls joined at their ends and spaced apart, a plate extending across the space between said closed ends and having a damper, a smoke-pipe communicating with the space formed by the inner wall of the drum and by the plate, means for admitting air into said space, and a partition between the walls of the drum agreeing substantially with the outline thereof and 45 serving to subdivide it into two communicating spaces, substantially as described. 50

In testimony that I claim the foregoing as my own I have hereto affixed my signature in the presence of two witnesses.

JAMES H. KLIPSTEIN.
